UNITED STATES PATENT OFFICE.

CHARLES A. ZEIGE, OF SPOKANE, WASHINGTON.

STEEL EXTRACTOR.

Application filed October 1, 1924. Serial No. 741,076.

To all whom it may concern:

Be it known that I, CHARLES A. ZEIGE, a citizen of the United States, residing at Spokane, in the county of Spokane and 5 State of Washington, have invented new and useful Improvements in Steel Extractors, of which the following is a specification.

This invention relates to improvements 10 in extracting tools.

It is a special object of this invention to provide a tool for withdrawing a bound drill steel from a hole. It is well known that when a steel becomes bound, or in the 15 parlance of the miner, "stuck", not only the drill is lost, but far more important, the whole round of holes is "lost".

One of the special features of my invention resides in an extracting tool having an 20 open bore extending throughout the length thereof whereby the extractor can be telescoped onto the projecting end of a bound drill steel.

A further feature of novelty resides in 25 an improved means for engaging or gripping the steel, whereby my improved extractor may be interposed between the formation and said means for exerting an extracting thrust lengthwise of the steel to 30 withdraw the latter from the formation.

My invention has many other features and 35 objects which will be more fully described in connection with the accompanying drawing, and which will be more particularly 40 set forth and pointed out in and by the appended claim.

In the drawing:—

Fig. 1, is a sectional view through a part 45 of a formation in which a drill steel is bound, and illustrating the manner of applying my improved extractor to the projecting end thereof.

Fig. 2, is a view in elevation of my extractor on an enlarged scale, showing the 45 same applied to a drill steel.

Fig. 3, is a longitudinal sectional view of the same.

Fig. 4, is a sectional view on line 4—4 of Fig. 3.

Fig. 5, is a side view of the gripper head.

Like characters of reference designate similar parts throughout the different figures of the drawing.

As illustrated, the formation is indicated 55 by 1, and the drill steel at 2. When the operating means is removed from the steel,

there is always a certain amount of projection which is indicated at 3, between the terminal end 4 of the steel and the breast or face 5 of the formation.

Next describing the structure constituting my invention, 6 designates one of a pair of coaxing companion members which is in the form of a sleeve having a hollow base 7 for abutment against the breast 5. 60 It will be noted that the base 7, which is annular in form, is somewhat enlarged with respect to the cylindrical portion 6. Said portion 6, has a bore 8, of a diameter sufficiently enlarged with respect to the drill to 70 telescope the drill 2, with suitable clearance, as shown. The bore 8, is preferably smooth but the periphery is threaded, as shown at 9.

The companion member 10, is likewise in the form of a sleeve and is provided with 75 internal threads 11, for engagement with the threads 9 of the base sleeve 6. The member 10 is provided with a hollow head 12, somewhat enlarged with respect to sleeve 10, and is equipped with a polygonal 80 portion 13, to which a wrench may be applied to rotate sleeve 10. The extreme outer end 14, is shaped to form a swivelling surface for engagement with my novel gripper means, which I will presently describe. The 85 edge 15, of the base section is preferably continuously smooth and flat, which form, in practice, is most effective as it finds a plurality of points of anchorage contact with the face 5. In case of necessity, however, 90 a wedge may be inserted where there is not sufficient plane surface against which the base may contact in a stable manner. As the base section 6, does not rotate, and as the section 10, is positively actuated, I will 95 refer to the former as the base section and the latter as the operating section.

I will next describe my improved gripping means.

Said means is in the form of a substantially flat member 16, having a laterally projecting handle portion 17. An opening 18 is formed in said gripper and the axis of said opening is at an acute angle to the plane of said gripper thereby forming gripping edges 19 and 20.

The operation of my improved device is as follows:—

When a drill is removed from the projecting end of a bound steel, I first telescope over the end of the steel, the united base and operating sections adjusted to a 110

starting position substantially as shown in Fig. 3. I next slip the gripper 16, over the end of the drill steel, as shown by dotted lines in Fig. 2, and move the gripper into engagement with the swivelling face 14. A wrench is then applied to the hexagonal portion 13 and a turning movement is imparted to the operating section 10. As section 10 is turned, the extracting tool is endwise lengthened, and the base 7, frictionally impinges against the breast, work or formation, whatever it may be, and the swivelling face straightens the gripper from the inclined position shown in dotted lines to the full line position shown in Fig. 2. By reason of the fact that the bore 18 is formed with its axis at an acute or oblique angle to the plane of the gripper, the latter will not pass over the steel unless disposed in the position shown in dotted lines. Hence, when pressure is applied to change the position of the gripper into the full line position, the edges 19 and 20, will bite against the drill steel so firmly that the gripper will remain stationary and positively hold the steel. This will be true even after the relatively sharp edges 19 and 20, have been dulled.

My invention also resides in the method of extracting bound drill steel which consists in applying thrust against the formation and against the steel to withdraw the latter.

While I have herein shown and described one specific form of my invention, I do not

wish to be limited thereto except for such limitations as the claim may import.

I claim:

A steel extractor comprising a jack formed of telescoping tubular members co-actingly threaded substantially throughout their respective lengths and adapted when in a starting position to have a major preponderance of their threads in coaxing engagement to distribute the load on substantially all the threads and shorten and stiffen the jack against distorting strains, the bore of the inner member permitting the jack to be telescoped onto the projecting end of the steel with the base of one member against the formation and the free end of the other member inside of the terminal end of the steel, an initially loose gripper on the projecting end of the steel endwise outside of said jack and adapted to be manually adjusted against the free end of the latter, and said jack having means whereby said tubular members may be relatively turned to lengthen said jack into endwise annular abutting swivelled engagement against and energize said gripper into rigid non-rotative and longitudinally fixed engagement with said steel during extracting of the latter, whereby an exclusively straight pull is exerted on the steel without imparting rotative or angular distortion thereto.

In testimony that I claim the foregoing as my own, I hereby affix my signature.

CHARLES A. ZEIGE.
